United States Patent Office

Des. 205,960
Patented Oct. 11, 1966

205,960

COIN HOPPER OR SIMILAR ARTICLE

Albert Hohmann, Brooklyn, N.Y., assignor to Taller & Cooper, Inc., Brooklyn, N.Y., a corporation of New York

Filed Feb. 15, 1965, Ser. No. 83,818

Term of patent 14 years

(Cl. D52—4)

FIG.1

FIG.2

FIG.5

FIG.4

FIG.3

FIGURE 1 is a plan view of a coin hopper embodying my new design.

FIGURE 2 is a side view; the opposite side being substantially the same in appearance.

FIGURE 3 is a front view thereof.

FIGURE 4 is a rear view of the hopper.

FIGURE 5 is a fragmentary perspective view of the upper portion of the coin hopper.

I claim:

The ornamental design for a coin hopper or similar article, substantially as shown and described.
